(57) **CLAIM**

The ornamental design for the lawn mower shade, as shown and described.

DESCRIPTION

FIG. 1 is a perspective view of a lawn mower shade showing my new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The broken line showing of a lawnmower is included for the purpose of illustrating environmental use only and forms no part of the claimed design.

1 Claim, 5 Drawing Sheets

FIG. 2

FIG. 3

FIG. 6
